9 Claims. (Cl. 200—33)

1

One object of the present invention is to provide a switching mechanism adapted to open and close a plurality of electrical circuits in alternating sequence.

Other objects of the invention are to provide a switch mechanism of robust and compact construction and to enable parts to be inspected, serviced and replaced easily and quickly.

In the drawings:

Fig. 1 is an end elevation of the mechanism of the present invention from within the casing;

Fig. 2 is a plan view from within the casing;

Fig. 3 is a front elevation of the mechanism within the casing with the casing cover open;

Fig. 4 is a detailed view of a mounting arrangement for the contact carrying levers and the linkage system therefor;

Fig. 5 is an elevation taken from behind the front cover plate and showing the speed varying mechanism details;

Fig. 6 is a rear elevation of the mechanism showing the gear train and auxiliary switch;

Fig. 7 is an end elevation of the mechanism showing the frictional drive detail.

The remote control mechanism shown in the accompanying drawings is housed in a casing 1 normally closed by a hinged cover 2 which is adapted to be retained in its closed position by a key-operated catch 3 carried in the said cover and adapted to engage behind a catch plate 4 mounted inside the casing.

The said mechanism is mounted within the casing upon a front frame 5 and a rear frame plate 6 held in parallel spaced relationship by distance pieces 7 carried upon the fixing bolts 8. The front frame plate 5 is hinged upon a pin 9 (see Fig. 3) disposed within one end of the housing thereby enabling the mechanism assembly to be swung into and out of the casing for inspection, repair or the like.

Normally, the said assembly is held within the casing by a spring loaded catch 10 which is mounted within the top of the casing so that it engages an edge of the front frame plate 5 and, when the cover is closed, is located in its plate-engaging position by a stud 11 on the inside of the cover (see Fig. 1).

A switch-operating cam, comprising two concentric discs 12, 13, clamped together by screws 14a and each having four peripheral lobes 14, is fixed upon a main spindle 15 journalled in the plates 5 and 6. The spindle 15 is rotatable within its bearings in the frame plates 5, 6, drive being transmitted thereto from an electric motor 30, through the motor spindle 49, a gear wheel 48 on 55

2

the said motor spindle which meshes (see Fig. 2) with teeth on the periphery of a driving disc 18, a pair of balls 19, and two spaced parallel driven discs 16, 17. The driven disc 16 is fixed to the main spindle 15, but the other driven disc 17 is slidable thereon and is urged towards the disc 16 by a compression spring 18a (see Figs. 2 and 7), to squeeze the balls 19 between the driving and driven discs 18—16, 17 thus to transmit the drive from the driving disc 18 to the driven discs 16, 17. The driving disc 18 is fixed on a lay spindle 20 which is also journalled in the plates 5 and 6 (see Fig. 7); the balls 19 are rotatably housed in the ends of a bifurcated arm 21 fixed to a spindle 22 which is journalled in the frame plates and is provided at one end with an arm 23; the said arms 21 and 23, and the spindle 22, are assembled in the form of a bell crank lever (see Fig. 5).

The arm 23 is provided, at its free end, with a laterally extending roller 24 which bears against the edge of a control or speed varying cam 25 whereby, when the said cam is rotated, the bell crank lever is turned about its axis and causes the balls 19 radially to traverse the driving disc 18 and driven discs 16, 17, for varying the speed at which the latter are rotated. The bifurcated arm 21 carrying the balls 19 is rotated by the driving disc in the direction which tends so to turn the bell crank lever that the roller 24 is held against the cam edge 25. This cam 25 is formed at one end of a sleeve 26 having an indicating disc 27 at its other end (see Fig. 1), the sleeve being fixed by a screw 28 to another spindle 29 journalled between the frame plates 5, 6. Drive is adapted to be imparted to the spindle 29 from the motor 30 through a train of speed reducing gears terminating in the gear 31 keyed to the said spindle 29. The indicating disc is visible through a window 32 (see Fig. 1) in the cover 2 and is marked with a scale so that the position of the cam 25 may be indicated visually by a pointer 33 (see Fig. 3) also visible through the said window.

The train of gears through which drive is transmitted to the spindle 29 consists, in addition to the terminating gear wheel, 31, of the gear wheels 34, 35, 35a, 36, 36a, 37, 37a and 38, 38a, drive being imparted to the gear train by the gear 34 which is fixed upon the spindle 20 whereon the driving disc 18 is keyed (see Figs. 2, 6 and 7). The gear wheels 37 and 37a are fixed to a spindle 39 which is also journalled between the frame plates 5, 6 and is capable of both rotary and longitudinal movement therein (see Fig. 1); normally the spindle 39 is held against longitudinal

movement by a spring loaded ball 40, which is located within the housing 40a (see Fig. 1) and engages one or other of the peripheral grooves 41 and 42 in the sleeve 40b. The spindle 39 is capable of longitudinal movement through a stroke equal to the distance between the centres of the grooves 41 and 42 and sufficient to enable the gear wheel 37 to be taken out of mesh with the gear wheel 36a so that the drive from the motor 30 to the gear wheel 37 and cam 25 is broken (see Fig. 2); however, the said gear wheel 37 is provided with a toothed hub or gear 37a, which meshes with and transfers the drive to the next pinion 38 of the gear train and is of such length that its engagement with the said pinion 38 is not broken by the longitudinal movement of the spindle 39. The grooved sleeve 40b is mounted freely on the spindle 39 and is secured to a button 44 by the thread 45. The button 44 projects through an aperture 41a in the cover 2 and is provided internally with an axial stud 44a (see Fig. 1) which abuts the end of the spindle 39 and is adapted to impart longitudinal motion to the said spindle, for taking the spring loaded ball 40 out of engagement with the peripheral groove 41 and into engagement with the other groove 42 when the button 44 is pushed thereby breaking the mesh between the gear wheels 36a and 37. Rotary motion may be imparted manually to the spindle by the button when the said gear wheels 36a, 37 are out of mesh and for this purpose the button has a lost motion connection to the spindle 39 by a transverse pin 46 (see Fig. 2) carried in the said spindle with its ends engaging elongated openings in the sleeve 40b. Such rotary motion enables any desired setting to be given to the speed-varying cam 25 before the mechanism is started or at any stage in the subsequent cycle of operations to enable the driven discs 16, 17, and the switch operating cam 12, 13, to be rotated at a definite speed. This speed may be maintained by allowing the gears 36a and 37 to remain disconnected, or may be increased gradually by pulling the button to re-engage the said gears with one another so that the motor drive may again be imparted to the cam spindle 29. If re-engagement of the said gears is attempted when their teeth are wholly or partially overlapping, the pull imparted to the button 44 displaces the sleeve 40b along the spindle 39 and compresses the spring 44b. A silent re-engagement of the gears is, therefore, made automatically by the spring when relative movement occurs between the gears 36a and 37.

Two adjustable fixed contacts 50, 51 (see Fig. 3) assembled to insulating terminal blocks 52, are mounted upon the front frame plate 5 whilst complementary moving contacts 53, 54, are carried by the levers 55 and 56 respectively. Each of the said moving contacts is provided with a conductor 57 which electrically connects the complementary moving contact to its terminal 58 carried in and insulated from the said frame plate. Each contact-carrying lever 55, 56 is rotatably carried upon a shaft 60 having eccentric end pins 60a journalled in a bracket 59 which is fixed to the said front frame plate 5 by screws 59a and one end of which serves as the pointer 33; the two shafts 60 are coupled together by linkage system 61, 62, 63, whereby any motion imparted to one of the said eccentrically journalled shafts is transferred to the other; the arrangement is such that the rotation of the shafts 60 varies the gap between the fixed and moving contacts, the space between one pair of contacts

being increased and the space between the other pair being decreased. The levers 55, 56, are formed respectively with tail pieces 64, 65, each being provided with an ear 66 which is urged towards the periphery of the twin switch-operating cam 12, 13, by a spring 67, which also tends to displace the complementary moving contact towards its fixed contact.

A phase-adjusting cam disc 68 is also fixed to the main spindle 15 concentrically with the switch operating cam 12, 13. A lever 69 is hinged on an adjustable bell-crank bracket 70 clamped to the front frame plate 5 and the said bracket is loaded by a spring 71. The free end of the lever 69 is urged against the phase-adjusting cam 68 by the inherent resiliency of a flexible moving contact carrying blade 72. When the bracket 70 is released by loosening the screw 70b it may be angularly adjusted by the turning of the eccentric stud 70a, thereby altering the times in the cycle of operations when the lever will ride off the lobes 68a of the phase adjusting cam 68. The moving contact carrying blade 72 is located between resilient contacts 73, 74, and is disposed centrally and clear of said contacts 73, 74, when the lever 69 is half-way along a cam lobe 68a; hence the flexing of the blade 72 makes and breaks the connection with the said resilient contacts. The resilient contacts 73, 74 are electrically connected respectively in the circuits of the coils 75 and 76, the coil 75 being adapted to be energised when the moving contact of the lever 69 raises the blade 72 and the coil 76 being adapted to be energised when the said lever allows the blade 72 to flex downwards. An armature 77, carried on the frame plate 5 between an over-centre spring 78 and a lever 79 connected to the linkage system 61, 62, 63, is adapted to be attracted by either coil, when energised to angularly displace the eccentrically mounted shafts 60. The coils are connected in parallel, through the contacts 73, 74.

The mechanism also comprises a manually operated switch 80 which is mounted in the cover (see Fig. 2) and is adapted to close the circuit of the motor 30 directly when in one position, or through an auxiliary switch 81 when in its other position. The moving contact carrying member 83 of the auxiliary switch 81 bears resiliently on the surface of a slotted roller 82, composed of insulating material, which is keyed to the main cam spindle 15, and is so located relatively to the switch-operating cam 12, 13, that the member 83 engages a slot 84 on roller 82 when one of the lever ears 66 is at the centre of a lobe 14. Thus when the motor is started, with the switch 80 in the position shown in Figure 2, the motor continues to run until a slot 84 on the roller 82 registers with the moving contact carrying blade 83 of the auxiliary switch 81. The blade 83 thereupon enters the slot 84 and opens the said auxiliary switch so breaking the motor circuit and bringing the mechanism to rest with one of the lever ears 66 located midway along a lobe 14 of switch operating cam 12, 13. The switch mechanism described above is particularly suitable for controlling the variable oscillations of a rocking furnace so that the furnace shell may be rocked through equal angular distances to each side of a dead centre position and so that, if desired, the said angular distances may gradually be increased to, and maintained at, a maximum.

For this purpose, there is mounted on the furnace structure a limit switch (not shown in the

drawings, and not forming a part of the present invention) which is closed by the furnace shell each time the latter reaches or passes through its dead centre position; the contacts 73 and 74 of the coils 75 and 76 are connected to the said limit switch so that an electrical impulse is fed through one or other of the said coils each time the limit switch is closed.

The furnace shell is adapted to be rocked automatically by a reversible electric motor under the control of reversing contactor switches actuated by the pairs of contacts 50, 53 and 51, 54; also, by the manual actuation of push button controls (which contactor switches, motor and push button controls, again are not shown in the drawings and do not form a part of the present invention) the shell-rocking motor may be started and stopped at will to set the furnace shell in, or substantially in, its dead-centre position prior to the commencement of the rocking operation under the control of the said contactor switches and the said two pairs of contacts.

Having brought the switch mechanism of the invention to rest with one of the lever ears 66 located mid-way along a lobe 14 of the switch-operating cam 12, 13, and having set the furnace shell in its dead-centre position, the switch 80 is changed over to connect the circuit of the motor 30 through the auxiliary switch 81 whereupon the said motor 30 and the shell-rocking motor may be started simultaneously with the furnace shell rocking in phase, or substantially in phase, with the levers 55 and 56, and the phase control means operated by the switch 72, 73, 74.

As the dual switch-operating cam 12, 13, rotates, it causes the pairs of contacts 50, 53, and 51, 54, to open and close alternately; the closing of one pair of contacts actuates a complementary contactor switch to drive the shell-rocking motor and the furnace shell in one direction, and the closing of the other pair of contacts actuates another contactor switch to reverse the said motor and the direction of travel of the furnace shell. The arrangement of the lobes of the said cam 12, 13, is such that a dwell exists between the opening of either pair of contacts and the closing of the other pair, during which dwell the shell-rocking motor, the furnace shell and the contents of the latter come to rest before the reversal of movement commences, thereby reducing strain on the said motor and any gear through which drive is transmitted to the said shell. This cycle of operations continues under the control of the switch mechanism of which the cam 12, 13, and contacts 50, 53 and 51, 54, form parts.

The angular distance through which the furnace moves is determined by the speed at which the cam 12, 13, rotates since this speed determines the period during which a pair of contacts remains closed.

At the commencement of the cycle of operations, the speed varying cam 25 is set so that the balls 19 are disposed near the periphery of the driving disc 18 and near the centre of the driven discs 16, 17. The latter and, therefore, the cam 12, 13, are thus driven at maximum speed. As the cam 25 is rotated by the motor 30 through the gear train 31, 34, 35, 35a, 36, 36a, 37, 37a, 38, 38a, the bell-crank lever 23, 22, 21, is allowed gradually to alter its position, under the action of the balls 19, by the rotation of the speed-varying cam 25; consequently the balls 19 travel radially between the discs 16, 17, 18, in a direction which takes them towards the centre of the driving disc 18 as seen in Fig. 5.

Thus the speed of the driven discs 16, 17, gradually falls, the closing period of the contacts 50, 53, and 51, 54, increases and consequently the angular rock of the furnaces increases.

If it is desired that the furnace should reach and maintain a predetermined maximum angular movement, the button 44 is depressed when this movement is attained, thereby breaking the drive to the cam 25 by disengaging the gears 36a and 37. Also, if it is desired that the furnace should rock through a predetermined angle at the commencement of the cycle of operations, the drive to the cam is again broken and the cam 25 is rotated manually by the button 44 and gears 31a, 38, 38a, and 31, until the desired position, indicated by the pointer 33 and the indicating disc 27, is attained.

Should the furnace shell continue to rock out-of-phase, that is through a greater angular distance to one side of its dead-center position than to the other side, the electrical impulse which is transmitted through the switch 72, 73, 74, and one or other of the coils 75, 76, by the closing of the limit switch operated by the furnace as it passes the dead centre position, flows when the moving contact 72 is in connection with one or other of the contacts 73 or 74. This occurs because the said moving contact is only in its central position, which ensures that both coil circuits are open, when the lever 69 is half-way down the steep face 68b of, or half-way along the slightly inclined face of a lobe 68a of the phase-adjusting cam 68. Further these intermediate positions are assured only when one of the lever ears 66 is at a central or substantially central position along a lobe 14 of the switch-operating cam 12, 13, that is, when the furnace is half-way between its two extreme positions. Thus, if intermediate positions are not assumed simultaneously, as when the furnace is rocking out-of-phase, the electrical impulse is able to energise a coil 75, 76. The energised coil attracts the armature 78 thereby angularly displacing, through the lever 79, the eccentrically journalled shaft 60 on which the lever 64 is mounted. This angular movement is transmitted through the links 61, 62, and 63, to the shaft carrying the lever 56. These angular movements of the shafts 60 cause the hubs of the complementary levers 50 to be displaced so that the moving contacts and the ears 66 tend to move nearer to or further away from the fixed contacts and the operating cam 12, 13, respectively. If the pairs of contacts 50, 53, or 51, 54, are closed, movement will be imparted to the ears so that the latter will meet the steep face of a lobe 14 earlier or later in the cycle of operations. If the contacts are open then the ears are in contact with lobes 14 and the movement will be transferred to the moving contacts causing them to move nearer to or further away from their complementary fixed contacts. No matter whether the movement is transferred to the ears of the moving contacts, the result is that the relative periods of opening and closing of the pairs of contacts are altered so that the time during which the furnace travels in one direction is altered at the expense of the time available for it to rock in the reverse direction, since, owing to the arrangement of the eccentric studs 60 and the linkage system 61, 62, 63, the lever hubs are moved so that there is an increase in the time during which one pair of contacts is closed and a decrease in the time during which the other pair of contacts is closed. Thus when the coil 75 is energised

there is an increase in the period during which the contacts 50, 53, are closed and a decrease in the period of closing of the contacts 51, 54; on the other hand, if the coil 76 is energised the closing period of the contacts 50, 53, is decreased and the closing period of the contacts 51, 54, is increased.

In order that the operation of the armature may be more delicate and sensitive, the armature 77 and lever 79 are counterbalanced by a weight 85.

The time taken for the angle of rock of the furnace to reach its maximum depends upon either the shape or the rate of rotation of the speed varying cam 25 and may be altered by replacing, for example, two of the gears of the gear train. To enable such a change to be effected quickly and easily, the gear wheels 31 and 38a are assembled to their respective shafts by spring clips 86 which engage grooves or channels in the said shafts. If desired, spare gear wheels may be carried in the casing 1.

Having described my invention what I claim and desire to secure by Letters Patent is:

1. A remote control switch comprising at least two pairs of electric contacts each pair consisting of a fixed contact and a movable contact and each pair being connected in a separate circuit, a substantially circular cam having a plurality of lobes on the periphery thereof, drive means for rotating said cam, control means connected to be driven by the drive means and operative automatically to vary the speed of said rotation, pivotal levers carrying the moving contact of each of said pairs and adapted for actuation by said lobes during said rotation whereby said circuits are opened and closed in a predetermined sequence determined by the shape of said lobes, and ancillary means for varying the relative periods of said actuation.

2. A remote control switch comprising at least two pairs of electric contacts each pair consisting of a fixed contact and a movable contact and each pair being connected in a separate circuit, a separate pivotal lever carrying the movable contact for each of said pairs, a separate eccentrically-journalled lever spindle for each of said levers, tensioning means on each of said levers normally adapted to maintain said movable contacts in closed-circuit relationship with the fixed contact of its pair, a substantially circular rotatable cam having a plurality of lobes on the periphery thereof adapted to overcome said tensioning means and to actuate said levers in alternating sequence during rotation of said cam whereby said circuits are opened in alternating sequence, a cam-spindle carrying said cam, variable speed rotating means for said cam-spindle, a linkage system interconnecting said eccentrically-journalled lever spindles for transmitting rotary motion from one to the other thereof thereby to vary the relative periods of said actuations, and means for transmitting rotary motion to one of said lever spindles.

3. A remote control switch as in claim 2 in which the means for transmitting rotary motion to one of said lever spindles comprises a pair of solenoids, an armature rotatably carried on one of said lever spindles and having an end projecting between said solenoids adapted for attraction thereto on energization of said solenoids, and means for intermittently energizing said solenoids whereby said armature is attracted to said energized solenoid thereby transmitting rotary motion to said lever spindle.

4. A remote control switch comprising cam actuated means for opening and closing a plurality of circuits in a sequence determined by the shape of the cam, drive means for rotating the cam, control means operative automatically and progressively to vary the speed of the cam rotation, and disconnectable means for driving the control means in synchronism with the cam drive means.

5. A remote control switch comprising cam actuated means for opening and closing a plurality of circuits in a sequence determined by the shape of the cam, drive means for rotating the cam, control means operative automatically and progressively to vary the speed of the cam rotation, disconnectable means for driving the control means in synchronism with the cam drive means, opposed magnet coils and armature means actuated alternatively by the coils and connected to reversely vary the relative periods during which the circuits are closed at any given speed of rotation.

6. A remote control switch comprising cam actuated means for opening and closing a plurality of circuits in a sequence determined by the shape of the cam, adjustable position drive means for rotating the cam at varying speeds, control cam means operative automatically and progressively to vary the position of the cam drive means to vary the speed of the cam rotation, disconnectable means for driving the control means in synchronism with the cam drive means, opposed magnet coils and armature means actuated alternatively by the coils and connected to reversely vary the relative periods during which the circuits are closed at any given speed of rotation, a manually operated starting switch and means associated therewith and operative to open the circuit at a given position of the circuit actuating cam.

7. A remote control switch comprising cam actuated switch means for opening and closing a plurality of circuits in a sequence determined by the shape of the cam, adjustable position drive means for rotating the cam at varying speeds, control cam means operative automatically and progressively to vary the position of the cam drive means to vary the speed of the cam rotation, an indicator disc connected to the control means, disconnectable means for driving the control cam means in synchronism with the cam drive means and a push button connected to effect manual disconnecting of the automatic control means and connected to permit manual adjustment of the drive means.

8. A remote control switch comprising cam actuated switch means for opening and closing a plurality of circuits in a sequence determined by the shape of the cam, adjustable position drive means for rotating the cam at varying speeds, control cam means operative automatically and progressively to vary the position of the cam drive means to vary the speed of the cam rotation, an indicator disc connected to the control means, disconnectable means for driving the control cam means in synchronism with the cam drive means and a push button connected to effect manual disconnecting of the automatic control means and connected to permit manual adjustment of the drive means, and a manually operable starting switch and means associated therewith and operative to open the circuit at a given position of the circuit actuating cam.

9. A remote control switch comprising cam actuated switch means for opening and closing

a plurality of circuits in a sequence determined by the shape of the cam, adjustable position drive means for rotating the cam at varying speeds, control means operative automatically and progressively to vary the position of the cam drive means to vary the speed of the cam rotation, an indicator disc connected to the control means, disconnectable means for driving the control means in synchronism with the cam drive means, means to effect manual disconnection of the 5 automatic control means and connected to effect manual adjustment of the drive means, opposed magnet coils and armature means actuated alternatively by the coils and connected to reversely vary the relative periods during which the circuits are closed at any given speed of rotation. 15
